UNITED STATES PATENT OFFICE.

ROY E. RICE, OF BUCYRUS, OHIO, ASSIGNOR TO ROBERTS & SCHAEFER COMPANY, OF CHICAGO, ILLINOIS, A CORPORATION OF ILLINOIS.

LIMIT SWITCH FOR ELECTRIC-DRIVEN HOISTS.

1,423,624.

Specification of Letters Patent. Patented July 25, 1922.

Application filed August 16, 1919. Serial No. 318,016.

To all whom it may concern:

Be it known that I, ROY E. RICE, a citizen of the United States, residing at Bucyrus, in the county of Crawford and State 5 of Ohio, have invented a certain new and useful Improvement in Limit Switches for Electric-Driven Hoists, of which the following is a specification.

My invention relates to limit switches 10 for electrically driven hoisting machines, wherein it is desired to limit the excursion of the hoist.

Such hoists are common in coal-handling machinery wherein the hoist is positioned 15 within a tower and the material to be handled is raised to a point at or near the top of the tower and then dumped. In such hoists it occasionally happens that after reaching the upper limit of the excursion, 20 the apparatus functions improperly and the bucket, for example, is carried higher than necessary. This will, of course, result in damage to the installation, and it is one of the objects of my invention to make such an 25 occurrence impossible. In order to do this I provide a switch which is connected to the hoisting drum and so arranged that it will be automatically tripped and the power for the hoisting motor cut off, in case the 30 bucket overruns the upper limit of its excursion.

My invention is illustrated more or less diagrammatically in the accompanying drawings, wherein—

35 Figure 1 is a front elevation; and

Figure 2 is a side elevation of Figure 1.

Like parts are indicated by like characters throughout.

A is a base board adapted to support my 40 limit switch mechanism and it is secured to the hoisting drum housing or frame.

B is the hoist drum shaft and carries in its end the pin B¹ which lies within the slot B² of the crank arm B³. This arm is 45 mounted upon the shaft B⁴ and journaled in the base board A. It carries on its other end the pinion B⁵ which is in mesh with the gear wheel C, carried upon the shaft C¹ which is secured to the base board A. The 50 gear wheel C has in it the segmental slot C² which is concentric with it. C³, C⁴ are stops adjustably positioned within the slot C².

D is a switch base mounted upon the base

board A. D¹ is a switch controller arm 55 pivotally mounted at D² upon the base D. D³ is a coil spring.

E is a spring switch arm secured to the controller arm D¹ through the insulated connection E¹. It has the contact face E² 60 adapted to contact the pole E³ which is connected to any suitable power source E⁴ here indicated diagrammatically. E⁵ is a similar pole similarly connected to the power source.

F is a lever pivotally mounted on the base D at F¹ and pointed at its lower end, as at F² to engage a notch in the end of the switch controlling arm D¹. It is connected to the controller arm D¹ by the toggle joint 70 F³.

The switch shown is in the power line of the hoisting motor.

Although I have shown my invention applied to an electric hoist, it is obvious that 75 it might equally well be applied to any apparatus of limited excursion wherein the power source is an electric motor. An example of such other use would be a drag line system of a funicular railway.

It will be understood that while I have shown in my drawings an operative device, still many changes might be made both in size, shape and arrangement of parts without departing from the spirit of my invention, and I wish, therefore, that my drawings be regarded as in a sense diagrammatic.

The use and operation of my invention are as follows:

When the drum shaft revolves it carries 90 with it by means of the slot and pin connection the small pinion and causes it to rotate. This, of course, rotates the gear wheel with which it is in mesh. The ratio between the pin and the gear wheel in the 95 present case is preferably 10 to 1, and the parts are so proportioned that the upward excursion of the bucket of the hoist is completed during less than one revolution of the large gear wheel. The switch parts are 100 normal in the position shown in Figure 1. The trip lever being exactly upright, it resists a tendency of the spring switch arm to throw it off center and serves to keep the assembly stationary. If, however, the 105 large gear wheel revolves too far, the stop in it will strike the trip lever and throwing it off center, will trip it and allow the

switch to fly open. This, of course, disconnects the current and at once and positively stops any further hoisting.

I claim:—

- 5 1. A limit switch for electric hoists comprising a switch element adapted normally to be in operative position, yielding means adapted to move it into inoperative position, a member, pivoted in unstable equilibrium, adapted to resist said yielding means, and means for tripping said member after a predetermined excursion of said hoist.
- 10 2. A limit switch for electric hoists comprising a switch element adapted normally to be in operative position, yielding means adapted to move it into inoperative position, a member, pivoted in unstable equilibrium, adapted to resist said yielding means, and means for tripping said member after a predetermined excursion of said hoist, comprising a wheel rotated by said hoist, and having means thereon for contacting said member.
- 15 3. A limit switch for electric hoists comprising a switch element adapted normally to be in operative position, yielding means adapted to move it into inoperative position, a member, pivoted in unstable equilibrium, adapted to resist said yielding means, and means for tripping said member after a predetermined excursion of said hoist, comprising a wheel continuously driven by the hoisting mechanism and so proportioned that a pre-determined rotation of said wheel is accomplished during one complete excursion of the hoist.
- 20 4. A limit switch for electric hoists comprising a switch element adapted normally to be in operative position, yielding means adapted to move it into inoperative position, a member, pivoted in unstable equilibrium, adapted to resist said yielding means, and means for tripping said member after a predetermined excursion of said hoist, comprising a wheel continuously driven by the hoisting mechanism and so proportioned that a pre-determined rotation of said wheel is accomplished during one complete excursion of the hoist, said rotation amounting to slightly less than one complete revolution.
- 25 5. A limit switch for electric hoists comprising a switch element, yielding means tending to move it into an operative position, a member pivoted in unstable equilibrium, adapted, when in such position, to resist said yielding means, and means for tripping said member, when in such position, to re-

sist said yielding means and means for throwing said member out of equilibrium after a predetermined excursion of said hoist.

6. A limit switch for electric hoists comprising a switch element, yielding means tending to move it into an operative position, a member pivoted in unstable equilibrium, adapted, when in such position, to resist said yielding means and means for throwing said member out of equilibrium after a predetermined excursion of said hoist, said member being so pivoted that the force of the yielding means is normally directed axially therealong and through the pivot point.

7. A limit switch for electric hoists comprising a switch element, yielding means tending to move it into an operative position, a member pivoted in unstable equilibrium, adapted, when in such position, to resist said yielding means and means for throwing said member out of equilibrium after a predetermined excursion of said hoist, said member being so pivoted that the force of the yielding means is normally directed axially therealong and through the pivot point, the switch element being notched on its upper surface to engage the lower end of said element when in unstable equilibrium.

8. A limit switch for electric hoists comprising a switch element, yielding means tending to move it into an operative position, a member pivoted in unstable equilibrium, adapted, when in such position, to resist said yielding means and means for throwing said member out of equilibrium after a predetermined excursion of said hoist, said member being so pivoted that the force of the yielding means is normally directed axially therealong and through the pivot point, the switch element being notched on its upper surface to engage the lower end of said element when in unstable equilibrium, the switch element and said member being pivotally secured to each other.

In testimony whereof, I affix my signature in the presence of two witnesses this 29th day of July, 1919.

R. E. RICE.
